UNITED STATES PATENT OFFICE.

OTTO G. LUYTIES, OF MOUNT VERNON, NEW YORK.

HEADLIGHT.

Application filed May 22, 1915, Serial No. 29,722. Renewed March 23, 1918. Serial No. 224,384.

To all whom it may concern:

Be it known that I, OTTO G. LUYTIES, a citizen of the United States, and residing at Mount Vernon, in the county of West-
5 chester and State of New York, have invented a new and Improved Headlight, of which the following specification is a full disclosure.

This invention relates to vehicle head-
10 lights. One of the objects thereof is to pro-
vide a simple and inexpensive light pro-
jecting device of highly efficient action. An-
other object is to provide a practical and ef-
fective light adapted to throw an illumina-
15 tion having certain desirable characteristics
especially suiting it for use as a vehicle
headlight. A more specific object is to pro-
vide a vehicle headlight of simple construc-
tion and efficient action in which a powerful
20 illumination is achieved without a dazzling
or blinding effect upon the eye.

Other objects will be in part obvious and
in part pointed out hereinafter.

The invention accordingly consists in the
25 features of construction, combination of ele-
ments, and arrangement of parts, which
will be exemplified in the structure herein-
after described and the scope of the appli-
cation of which will be indicated in the fol-
30 lowing claims.

In the accompanying drawing, in which is
shown one of various possible embodiments
of this invention, Fig. 1 is a diagrammatic
35 sectional view of the same. Fig. 2 is a front
elevation on a smaller scale.

Similar reference characters refer to simi-
lar parts throughout both views of the
drawing.

Referring now to Fig. 1 of the drawing,
40 there is indicated at 1 a parallel-ray reflector,
in this case a reflector of the parabolic form,
although the above term is used to compre-
hend equivalent devices such as Mangin
mirrors.

45 Mounted in this reflector in any suitable
manner so as to receive electric current, is
a lamp bulb 2 having the plug portion 3 by
which it is supported. The filament of this
bulb is indicated at 4 and is concentrated
50 or brought within a small compass in order
to give, in so far as is practicable, point il-
lumination. This filament is positioned sub-
stantially at the focus of the reflector 1 and
hence the rays emitted therefrom are re-
55 flected in substantially parallel relation.

The glass portion 5 of the bulb 2 is

elongated in a direction axial to the reflector,
as shown, and is preferably substantially
cylindrical in shape. In this manner a suffi-
cient heat radiating surface for a given fila-
60 ment is gained and a sufficient volume with-
in the bulb attained to admit of a proper
vacuum and yet the greatest cross-section
transverse to the axis of the reflector is held
to a minimum. To render this matter and 65
the advantages of this construction more
clear, it may be noted that with a given il-
luminating power with a given type of light,
there is a minimum to which the heat radi-
ating surface can be reduced. Also, in the 70
practicable methods to producing a vacuum
in electric light apparatus, it is desirable
that the bulb have a considerable volume in
order that the residual fluid therein be small
75 relative to its cubic contents. These require-
ments are fulfilled in the above construction,
and yet, by elongating the bulb in a direc-
tion parallel to the reflected light rays, the
area of the reflector obscured by the bulb
80 is reduced to a minimum and a proportion
of its light rays of greatest intensity are
given unobstructed reflection, as for example
the ray indicated at 6, instead of being forced
through two thicknesses of glass with at-
85 tendant losses, as would be the case if the
bulb were spherical and of the same cubic
contents. The bulb, moreover, is preferably
reduced in cross-section with respect to the
maximum cross-section of a bulb of the ordi-
90 nary form in general use of the same candle-
power and type. It may also be noted that
the filament is preferably wound in a spiral
with its axis substantially coincident with
the axis of the reflector, as in this way the
95 optical efficiency of the device is increased.

Considering, now, the construction of this
bulb more in detail, it may be noted that it
is given clear transparent form substantial-
ly up to the plane passing through the fila-
100 ment transversely to the axis 7 of the re-
flector. In this manner, the entire illumina-
tion in the annular space between rays such
as 6 and 8, which comprises nearly half of
the light emitted by the filament 4, is strong-
105 ly reflected in a clear beam as indicated by the
area 9 in Fig. 2 of the drawing. The bulb
surface from the transverse plane through
the filament up to the tip 10 is preferably
frosted and hence the light reflected between
110 the rays 8 and 11 is softened and diffused
and irregularly reflected, and hence forms
an annular beam as indicated at 12 in Fig.

2 of the drawing, of far less intensity than the beam 9. As I have found it desirable to secure a light diffusing area as large as is practicable without interfering with other 5 features of this invention, it is desirable that the concentrated filament be located not at the center but about two-thirds of the length of the bulb, or more, from the tip. In this manner the light diffusing surface is increased 10 and its intensity of illumination, and hence blinding effect on dark roads, is reduced. Furthermore, the rays from the source of light fall upon the diffusing surface at the sides of the bulb at a slight angle 15 rather than normally to its surface, and hence the diffusing effect is increased.

The frosted portion of the bulb 2, as far as the line 13, is preferably not only frosted but given a slight color, preferably 20 yellow, which aids in softening its effect upon the eye and renders it better suited to act as an illuminated background for the bright area 9.

In order to render more clear the action 25 of the latter feature, it may be noted that the blue and violet rays of the spectrum are most irritating to the eye. Furthermore, the outer portions of the retina of the eye, although less sensitive than its center, are relatively more sensitive to blue 30 and violet rays, and hence the cutting off of rays of this character from the latter portion of the retina, as for example those radiated outside the point on which the 35 vision is centered, is correspondingly important. I have found that the use of colored light as above set forth is of peculiar value and, furthermore, that a yellow light is best suited to accomplish the objects 40 in view as it not only cuts down the blue and violet rays but has a higher illuminating power than, for example, the light thrown through an amber glass.

The limit 13 of the colored band is determined 45 by the ray 11 passing to the outermost point of the reflector, and it may here be noted that the terms "outer" and "inner" with respect to the reflector, are used in a relative sense to denote distance from the 50 axis 7. The remaining end portion or tip of the bulb is preferably frosted and serves to give a diffused light which aids in illumination of adjacent objects. Its cross-sectional area with respect to the axis 7 is 55 relatively small, as indicated at 14 in Fig. 2 of the drawing, and does not materially cut down the area of the bright reflected beam 9.

The action of the above apparatus will be 60 substantially clear from the description given but it may be noted that the light emitted by the filament is economically used, partially by reason of the shape of the bulb and partially by reason of the fact that a 65 large proportion is projected in substantially

parallel form, although the rays are optically so disposed as to cut the objectionable glaring or blinding effect to a minimum. It is also to be noted that by the shape of the diffusing portion surrounding the filament in substantially cylindrical form, a large part of the rays passing radially outward from the filament strike this member at an angle and thus enhance the irregular refracting effect. The translucent portion, 70 by which is meant a portion which transmits light with some impedance of diffusion, is arranged about the bright central beam and thus gives an illuminated background which much reduces the blinding effect of 75 the central beam. In the use of the apparatus, there is thus thrown a far-reaching beam of white light containing the usual percentage of blue and violet rays surrounded by a somewhat diffused beam of 80 yellowish light in which the latter rays are greatly reduced. Due to this, the appearance of the headlight to one looking directly into it is that of a small bright shining surface at and around the center of the rear 85 of the reflector surrounded by a softly lit yellowish annular portion which, as above set forth, reduces the glaring effect. This form of illumination, moreover, is not only easily borne by the eye looking directly into 90 the headlight and effective for the user of the light, but is peculiarly suited for practical use in which passing vehicles or 95 pedestrians are usually at one side of the bright ray when close to the light and hence are exposed only to the yellowish diffused light. It is to be understood, however, that the broader features of this invention are not limited to this coloring effect or to 100 other details of the above illustrative embodiment.

It will thus be seen that there is provided simple and inexpensive apparatus in which the various objects of this invention are achieved and which is well suited to meet 110 the requirements of hard, practical use. It will also be seen that this is achieved without a wasteful dimming effect as by partially opaque bodies, but by an economical handling of the light rays.

As many changes might be made in the above construction, and as many apparently different embodiments might be made of this invention without departing from the scope thereof, it is intended that all 120 features herein described or shown in the accompanying drawing shall be interpreted as illustrative and not in a limiting sense.

Having thus revealed this invention, I claim as now and desire to secure the following combinations of elements, or equivalents thereof, by Letters Patent or the United States:—

1. In a vehicle headlight, in combination, 125 a parallel-ray reflector, a source of light, the 130

- inner portion of said reflector being directly exposed to said source of light and adapted to project light therefrom and translucent diffusing means normally interposed between said source of light and an outer zone of said reflector whereby said reflector is adapted to throw a beam of undiffused reflected light surrounded by diffused light.
2. In a vehicle headlight, in combination, 10 a parallel-ray reflecting surface, a source of light substantially at the focus of said surface and adapted to throw a strong beam reflected from said surface, and means adapted to reflect light from said source 15 and emit said light in diffused form and of reduced intensity from an annular area surrounding said beam, said source of light being in the form of a filament of an electric bulb and said means comprising irregularities on the surface of the forward portion of 20 said bulb and extending between said source of light and the outer portions of said reflecting surface.
3. In a vehicle headlight, in combination, 25 a parabolic reflecting surface, a source of light substantially at the focus of said surface and adapted to throw a strong beam of reflected light from the inner portion of said surface, and an annular colored translucent member interposed between the outer 30 annular portion of said reflecting surface and said source of light, whereby there is thrown a strong beam of reflected light surrounded by less penetrating colored 35 light.
4. In a vehicle headlight, in combination, 40 a parallel-ray reflector, and an electric light bulb having a concentrated filament substantially at the focus of said reflector and having its glass materially elongated in cylindrical shape in the direction of axis of said reflector and of relatively reduced maximum diameter in a transverse plane, said bulb being mounted with its rear wall 45 forwardly of said reflector and the reflecting surface in the rear of said wall being exposed to light passing through said wall.
5. In a vehicle headlight, in combination, 50 a curved reflector, a source of light, and yellowish translucent diffusing means interposed between said source of light and an outer portion of said reflector, the inner area of said reflector being exposed to substantially full illumination from said source of light whereby said reflector throws a 55 beam of strong light surrounded by yellowish light of less intensity.
6. In a vehicle headlight, in combination, 60 a parallel-ray reflecting surface, an electric light bulb having a concentrated filament substantially at the focus of said surface and having its glass materially elongated in cylindrical form in the direction of the axis of said reflector and adapted to throw a strong beam of light reflected from said 65 reflecting surface, and means adapted to reflect light from said source and emit said light in diffused form and of reduced intensity from an annular area surrounding 70 said beam.
7. In a vehicle headlight, in combination, 75 a parallel-ray reflector, and an electric light bulb having a concentrated filament substantially at the axis of said reflector and formed as an elongated cylinder lying with its length extending in a direction substantially parallel to that in which the reflector throws its light, the glass of said bulb at its rear portion being substantially clear and having a frosted forward portion extending between said filament and the outer portions of said reflector whereby there is thrown a beam of strong light surrounded by diffused light of less intensity.
- In witness whereof, I hereunto subscribe 80 my name, as attested by the two subscribing witnesses.

OTTO G. LUYTIES.
